UNITED STATES PATENT OFFICE.

ALFRED J. HEINKE, OF TOWACO, NEW JERSEY, ASSIGNOR TO H. R. MALLINSON & CO. INC., OF NEW YORK, N. Y., A CORPORATION OF DELAWARE.

DESIGN FOR A TEXTILE FABRIC OR SIMILAR ARTICLE OF MANUFACTURE.

Application filed October 24, 1928. Serial No. 28,602. Term of patent 3½ years.

To all whom it may concern:

Be it known that I, ALFRED J. HEINKE, a citizen of the United States of America, residing at Two Bridges Road, Towaco, in the county of Morris and State of New Jersey, have invented a new, original, and ornamental Design for Textile Fabric or Similar Article of Manufacture, of which the following is a specification, reference being had to the accompanying drawing, forming part thereof, and showing a face view of a piece of textile fabric embodying my design, the shading being used to indicate difference in colors and not to designate specific colors.

In the drawing, the figure is a view of a portion of fabric or the like showing the new design. A complete unit is enclosed between the broken lines A, B, C, and D, and this unit is repeated in the relation wherein the angle DAB coincides with angle CX Y indefinitely throughout the fabric as shown.

I claim:

The ornamental design for a textile fabric or similar article of manufacture substantially as shown and described.

ALFRED J. HEINKE.
